UNITED STATES PATENT OFFICE

2,074,653

WHEEL CHAIR

James Larsen, Plainville, Conn.

Application May 25, 1935, Serial No. 23,488

1 Claim. (Cl. 155—30)

The present invention relates to new and useful improvements in wheel chairs and has for its primary object to provide, in a manner as hereinafter set forth, a device of this character embodying a novel construction, combination and arrangement of parts through the medium of which a patient may be transferred from a bed thereonto and vice versa without discomfort and with a minimum of labor.

Another very important object of the invention is to provide a wheel chair of the aforementioned character which may be conveniently adjusted vertically to the level of beds of different heights.

Still another very important object of the invention is to provide a wheel chair of the type including adjustable back and leg rests, together with novel means connecting said back and leg rests through the medium of which they may be adjusted in unison or independently, as desired.

Other objects of the invention are to provide a wheel chair of the character described which will be comparatively simple in construction, strong, durable, highly efficient and reliable in use, compact, light in weight, attractive in appearance, comfortable and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in side elevation of a wheel chair constructed in accordance with the present invention.

Figure 2 is a horizontal sectional view, taken substantially on the line 2—2 of Figure 1.

Figure 3 is a top plan view of the vertically adjustable frame.

Figure 4 is a detail view in vertical section, taken through a rear portion of the invention.

Figure 5 is a detail view in vertical transverse section, taken substantially on the line 5—5 of Figure 2.

Figure 6 is a view in vertical longitudinal section through a rear portion of the device, showing one of the elevating screws.

Figure 7 is a detail view in front elevation of the bolster.

Referring now to the drawings in detail, it will be seen that the embodiment of the invention which has been illustrated comprises a stationary frame 1 having mounted beneath its forward end portion a bolster designated generally by

the reference numeral 2, said bolster 2 including vertical members 3 and cross members 4. An axle 5 is mounted beneath the bolster 2 and journaled on said axle are front wheels 6. A single rear wheel 7 is swivelly mounted on a cross member 8 of the stationary frame 1. Threadedly mounted in the front and rear end portions of the stationary frame 1 are vertical screws 9 which are provided with operating wheels 10. Mounted on the screws 9 for vertical adjustment is a frame 10 which is designated generally by the reference numeral 11, said frame 11 including side members 12 having series of notches 13 in the rear end portions thereof. Adjacent each of the notches 13 in one of the side members 12 are eye screws 14, the purpose of which will be presently set forth.

Mounted on the forward portion of the frame 11 is a seat 15 to the rear end of which a back 16 is hingedly connected, as at 17. A substantially U-shaped support 18 is provided for releasably securing the back 16 in adjusted position, said support being hingedly connected, at its ends, to an intermediate portion of said back 16, as at 19. The support 18 is selectively engageable in the notches 13 and mounted on said support is a hook 20 engageable in the eye screws 14 for preventing disengagement of said support from said notches. The portions of the support which are engaged in the notches 13 are recessed, as at 21, (see Figure 4).

The reference numeral 22 designates leg rests which are hingedly mounted, as at 23, on the forward end of the frame 11. Braces 24 are hingedly mounted, as at 25, on the leg rests 22 for supporting said leg rests in adjusted position. The braces 24 extend across the lowermost member 4 of the bolster 2 and have mounted therein pins 26 engageable with said lowermost member 4 for supporting the leg rests 22. The pins 26 are selectively engageable in openings 27 (see Figure 2) which are provided therefor in the braces 24.

Mounted on the lower end portions of the leg rests 22 are interchangeable and invertible foot rests 28. Rigidly secured to the ends of the foot rests 28 are angular brackets 29 which are adapted to embrace the leg rests 22 therebetween. The brackets 29 are provided with openings for the reception of spring projected pins 30 which are slidably mounted in the leg rests 22 for removably mounting the foot rests 28 thereon.

The reference numeral 31 designates arm rests which are hingedly mounted at one end, as at 32, on the back 16. The forward ends of the arm rests 31 are hingedly connected, as at 33, to the

upper ends of supports 34. Hinges 35 connect the supports 34 to the upper ends of the leg rests 22 and it will be observed that said hinges 35 are secured to the upper sides of said leg rests 22. 5 Coil springs 36 extend between the arm rests 31 and the supports 34 in a manner to assist in raising the back 16.

Hingedly mounted beneath the frame 1 is a substantially U-shaped support 37 which is adjacent the swivelled rear wheel 7. Resilient latches 38 depend from the frame 1 for engagement with the support 37 for releasably securing said support 37 in raised or inoperative position. The support 37 is of a length to partially support the rear end of the chair in a manner to prevent lateral or swinging movement of said rear end when transferring a patient. In addition, the member 37 provides a more stable support for the rear end of the chair than would be possible with 20 the single wheel 7.

Briefly, the operation of the chair is as follows:—

To transfer a patient from a bed to the chair, the back 16, arm rests 31, supports 34, and the leg rests 22 are swung to a horizontal position on the frame 11, the support 18, of course, being disengaged from the notches 13 to permit this. The chair is then rolled to a position closely adjacent one side of the bed and the screws 9 are actuated 30 to secure the desired vertical adjustment. The patient may then be maneuvered from the bed on to the chair without discomfort.

Of course, after the patient has been placed on the chair the back rest 16 may be raised to the desired inclination where it will be supported by the member 18. When the back 16 is swung upwardly the arm rests 31 are also raised. This operation also swings the supports 34 upwardly and forwardly in a manner to lower the leg rests 35

22. However, should it be desired to retain either or both of the leg rests 22 in horizontal or raised position, this may be accomplished by simply inserting the pins 28 in the desired openings 27 for engagement with the lowermost cross member 4 of the bolster 2. It will be observed that the hinges 35 will permit swinging movement of the members 22 and 34 independently of each other. Should it be desired to raise the foot rests 28 on the leg rests 22, the spring actuated pins 30 are pushed inwardly to permit said foot rests to be removed and replaced on said leg rests 22 in inverted position. It may be well to here state that the pins 30 will engage in the openings provided therefor in the angular brackets 29 when the foot rests 28 are in either of the aforementioned positions on the leg rests 22. It will be understood, of course, that when the chair is being rolled from place to place, the support 37 is in raised position. 15

It is believed that the many advantages of a wheel chair constructed in accordance with the present invention will be readily understood, and although a preferred embodiment of the invention is as illustrated and described, it is to be understood that changes in the details of construction and in the combination and arrangement of parts may be resorted to which will fall within the scope of the invention as claimed. 20

What is claimed is:—

A wheel chair comprising a frame, a back hingedly mounted on the frame, said back having offset longitudinal side edge extensions to provide shoulders intermediate its upper and lower edges, arm rests hingedly connected to said shoulders at the forward side of the back and an adjustable brace for the back hingedly attached at one end to the edge of said shoulder at the rear of said back. 30 35

JAMES LARSEN.
